GAME

Joseph Polanco, New York, N. Y.

Application October 15, 1937, Serial No. 169,261

1 Claim. (Cl. 273—134)

This invention relates to games and the primary object of the invention is to provide an improved game which will be of interest to both young and old, and which will require considerable skill and strategy to be played successfully.

Another object of the invention is to provide an improved game in which the game board is divided into two different camps each defended by an army.

A further object of the invention is to provide a game which will show a real battle between two modern armies having the aid of airplane.

A still further object of the invention is to provide an improved game which can be placed upon the market at a reasonable cost.

With these and other objects in view, the invention consists in the novel construction, arrangement and formation of parts as will be herein-after more specifically described, claimed and illustrated in the accompanying drawing, forming a part of this specification, in which drawing:

Figure I is a plan view of the game board.

Figure II shows the special die used during playing. Only used in one of the two different ways this game can be played.

Figure III is a front view of one of the soldiers used in the game.

Figure IV is a perspective view of one of the airplane playing pieces employed.

Referring to the drawing in detail wherein similar reference characters designate corresponding parts throughout the several views;

The game board may be formed of cardboard or any other suitable material and has its end portion marked to define the camps 1 and 2 of opposing armies. These camps are located midway the width of the game board in opposed relation to each other and along their sides and outer ends are borders 3 and 4 which are preferably colored yellow although any desired color may be used. Spaces 5 and 6 which have borders 7 and 8 are provided at opposite sides of the camp and constitute spaces in which "dead" opponents are to be placed when taken. The borders 7 and 8 will preferably be brown, but it is to be understood that they may be any color in contrast with the yellow borders 3 and 4. There has also been provided a brown border 9 extending entirely about margins of the playing board. Flying fields 10 and 11 having yellow borders 12 and 13 are marked upon the game board in advance of the spaces 5 and 6 and within the spaces 10 and 11 are drawn airplanes 14 and 15, the airplanes 14 being colored yellow and the air-

planes 15 blue in order that they may be readily distinguished from each other as each army is to defend its own flying field and attempt to reach the opponent's flying field. The cockpits 14^a and 15^a of the airplanes are colored red and the triangles 16 and 17 which constitute entrances to the flying fields are also colored red, but it is to be understood that the entrance triangles and the cockpits may be of any desired color which will be in contrast to the yellow borders 12 and 13 and the yellow and blue airplanes 14 and 15. Midway between the companion flying fields and in advance of the camps are spaces 18 and 19 set off by yellow borders 20 and 21 and at opposite sides of these spaces are passways 22 and 23 which are colored red and divided to form a plurality of blocks 22^a and 23^a. These passways or runways 22 and 23 constitute lanes along which the game pieces 24 may move from the camps 1 and 2 onto the battle-field. The game pieces are shaped to represent men, as shown in Figure 3, and each player will have the same number of game pieces or soldiers. In the preferred embodiment of the invention, each player has twenty soldiers which are initially placed in the camps 1 and 2, the soldiers or game pieces of one player being yellow and placed in the camp 1 and the soldiers or game pieces of the other player being blue and placed in the camp 2. Each player has six airplanes 25 and initially places three of them in each of his flying fields 10 or 11, the airplanes of the player having the camp 1 and the flying fields 10 being colored yellow and the opposing airplanes which are placed in the flying field 11 being colored blue. The space 26 which extends transversely across the board between the camps and flying fields of the opposing armies constitutes the battle-field. This battle-field is colored green so as to set it off from the remainder of the board and it is divided into a plurality of blocks 27 which are arranged in rows extending transversely and longitudinally of the playing board.

When this game is played, the yellow soldiers or game pieces are placed in the camp 1 and the blue soldiers or game pieces placed in the camp 2. The yellow airplanes are placed in the flying field 10 and the blue airplanes upon the flying field 11. The players may take turns and move their game pieces or soldiers in step by step movement along the block of the runways 22 and 23 and after a game piece has reached the battle-field it may be moved in step by step movement towards the opponent's end of the board. A game piece or soldier 24 may only be moved forwardly or transversely of the board and not back towards

its own camp. The object is to jump as many of the opponent's game pieces as possible and also endeavor to reach the entrance to one of the opponent's flying fields without being jumped. 5 Upon reaching the entrance 16 or 17 of the opponent's flying field, the game pieces may then be moved onto the flying field and come to rest upon the cockpit 14^a or 15^a of the airplane marked thereon and, when this is accomplished, the 10 soldier becomes an aviator. The player who has succeeded in moving a game piece onto an opponent's flying field may move one of his airplanes from his flying field through the entrance 16 or 17 and onto the battle-field. An 15 aviator may move not only forwardly and transversely of the battle-field but may also move back towards his own camp but must move in straight lines when moving from one block 21 to another. The aviator also has the privilege of moving more 20 than one block in order to jump an opponent whereas a soldier may only move from one block to another instead of passing two or more blocks in order to jump an opponent. An aviator also has the privilege of jumping an opponent approaching the battle-field through one of the runways 22 or 23 whereas a soldier is not allowed to enter a runway after arriving upon the battle-field. Instead of the game pieces being merely 25 moved one block at a time as the players take their turn, the number of blocks to be moved may be controlled by chance. In order to do so, there has been provided a special dice for each player. One of the dice has been shown in Figure 2 and indicated by the numeral 28. Referring to this 30 figure, it will be seen that the dice has a single spot 29 upon four side faces, the other two faces of the dice which are in opposed relation to each other being provided with two spots 30. The dice is thrown and if the face presented upwardly has one spot a game piece or soldier will be moved one 35

block, whereas, if the face of the dice presented uppermost has two spots, a game piece may be moved two spaces or if so desired two game pieces may be moved one space. The dice will only be used for controlling movements of the game pieces 5 or soldiers 24 as the aviators represented by the airplanes 25 may be moved more than one block in a straight-away direction. When the game pieces or the aviators are jumped, they are placed in the spaces 5 and 6 provided for dead enemies 10 and will remain there until the game is over. The player who succeeds in taking all of the opponent's soldiers wins the game.

Having thus described the invention, what I claim is:

In a game apparatus, a game board, end portions of said board being marked to provide opposing camps located midway the width of the board at opposite ends thereof and flying fields constituting promotion stations in corner portions of the board at opposite sides of the camps, 20 said flying fields projecting forwardly beyond the camps and terminating in spaced relation to ends of the board to provide concentration areas at opposite sides of rear portions of said camps, space 25 between the projecting portions of companion flying fields being marked to provide intermediate areas in front of the camps and pathways leading from the camps at opposite sides of the intermediate areas and divided into blocks, the mid- 30 section of the board between opposing flying fields and pathways constituting a battle-field extending the full width of the board and divided into blocks arranged in rows extending transversely of the board and longitudinally thereof, and said 35 flying fields having entrances leading from opposed blocks adjacent opposite sides of the battle-field.

JOSEPH POLANCO.
